Primary Examiner—Kay H. Chin[57] **CLAIM**

The ornamental design for a support trolley for a CPU
(computer processing unit), as shown and described.

DESCRIPTION

FIG. 1 is a top and side perspective view of a support trolley for a CPU (computer processing unit) showing my new design;

FIG. 2 is a top plan view thereof;

FIG. 3 is a side elevational view thereof, the opposite side elevational view being a mirror image of that shown;

FIG. 4 is a front elevational view thereof; and,

FIG. 5 is a rear elevational view thereof.

FIG.1.

FIG. 2.

FIG. 3.

FIG.4.

FIG. 5.
